Patented Oct. 13, 1959

186,301

WASH-BASIN

Julius Hurwitz, Bayside, N.Y.

Application June 24, 1958, Serial No. 51,503

Term of patent 3½ years

(Cl. D4—2)

Fig. 1 is a top plan view of a wash-basin, showing my new design;

Fig. 2 is a vertical sectional view taken on the line 2—2 of Fig. 1;

Fig. 3 is a bottom plan view of Fig. 1; and

Fig. 4 is a rear elevational view of Fig. 1.

The outside surface is smooth.

I claim:

The ornamental design for a wash-basin, as shown and described.
